COMBINED RAZOR AND BLADE HOLDER

Robert C. Nolan and Charles E. Herie, Studio City, Calif.

Application November 1, 1956, Serial No. 43,635

Term of patent 3½ years

(Cl. D4—3)

Fig. 1.

Fig. 2.

Fig. 3.

Fig. 1 is a perspective view of a combined razor and blade holder, showing our new design.

Fig. 2 is a front elevational view thereof on a reduced scale.

Fig. 3 is a plan view on the scale of Fig. 2.

The side of the holder that is not shown is the same as the side that is shown. The back is substantially plain and unornamented. The phantom showing of the razor and blades is depicted for illustrative purposes only.

We claim:

The ornamental design for a combined razor and blade holder, substantially as shown and described.
